MACHINE FOR MAKING PREFABRICATED
STEEL STRUCTURAL MEMBERSOtto Howard Lucy, Whittier, Calif., assignor, by
mesne assignments, to Herman Robert Triplett,
Whittier, Calif.

Application May 13, 1949, Serial No. 93,051

3 Claims. (Cl. 140—112)

1

This invention relates to and has for an object the provision of a machine and method for fabricating structural units particularly adapted for use as components of completely prefabricated panels for reinforcement of concrete structures.

Prefabricated reinforcing panels are formed with relatively horizontal and vertical members uniformly spaced apart lengthwise and crosswise of the panels at distances generally conforming to the spacing of studs in a wooden frame and the members thereof are of a length and width which are multiples of the spaces between corresponding members.

The panels are formed with corresponding parallel members which are herein referred to as studs and relatively right angular members herein referred to as rods. The studs may be disposed either horizontally or vertically in the panels and are of composite character. Each stud includes a pair of parallel rods spaced apart throughout its length as by means of short spacers which are preferably of the same cross sectional form and size as the parallel rods to which they are preferably welded for providing a rigid unit which when arranged flatwise and disposed horizontally or edgewise and disposed vertically in a panel and in either case welded at points of intersection to the relatively right angular rods of the panel provide a rigid panel structure of variable length and height capable of reinforcing a concrete wall or floor when imbedded therein.

Hence, a primary object of this invention is to provide an automatically operative machine which is arranged to fabricate the composite studs from wire which is fed to and through the machine and successively cut, feed and weld the spacers to the two spaced parallel rods and cut the completed studs of predetermined length and width in a continuing sequence of operations, and in readiness for receiving the relatively right angular rods for completion of the panels.

Another object is to provide a comprehensive system of hydraulic and air operated media under electrical control for effecting the timed and successive forming, welding and cutting operations in regular sequence.

It is a further object to form the parallel rods of the studs with inwardly bent portions at their points of junction with the spacers therebetween and of such a depth as to accommodate the relatively right angular rods of the panel in substantially the same plane as the stud rods, and, to such end to provide means in the machine for

2

thus forming the stud rods prior to the welding of the spacers thereto.

A still further object is to provide means for straightening the wires as they are unwound from reels and advanced to operative positions to the forming means and more maintaining the straightness of the wires as they are moved through the machine.

I have shown a preferred embodiment of the invention in the accompanying drawings, subject to modification within the scope of the appended claims, without departing from the spirit of the invention. In said drawings:

Fig. 1 is a side elevational view of a satisfactory type of machine embodying my invention;

Fig. 2 is a front elevational view as viewed in the direction of arrow 2 in Fig. 1;

Fig. 3 is a side elevational view in the plane of Fig. 1 showing a wire straightening mechanism through which the work is fed in parallel lines into operation with successive elements of the machine;

Fig. 4 is a plan view of the straightening mechanism as viewed in the direction of arrow 4 in Fig. 3;

Fig. 5 is a side elevational view of a hydraulic feeding unit;

Fig. 6 is a cross sectional view of the same on line 6—6 of Fig. 5;

Fig. 7 is a fragmentary sectional view in the plane of line 7—7 of Fig. 6;

Fig. 8 is a transverse elevational view of a forming unit for recessing the parallel rods of the studs at corresponding points;

Fig. 9 is a fragmentary transverse section of the forming dies on line 9—9 of Fig. 8;

Fig. 10 is a fragmentary plan view of the forming dies of Fig. 8 with the straightened dies in position for a forming operation, as viewed in the direction of arrow 10 of Fig. 9;

Fig. 11 is a transverse elevational view of a welding unit on line 11—11 of Fig. 1;

Fig. 12 is a sectional elevation of one of the welders of the welding unit shown in Fig. 11;

Fig. 13 is an elevational view, partly in section, of a vise for holding the spacers during a welding operation;

Fig. 14 is another view of the mechanism of Fig. 13 as viewed in the direction of the arrow 14 of Fig. 13;

Fig. 15 is a sectional elevation of a spacer feeding mechanism arranged for delivering the spacers intermittently to the vise of Fig. 13 preparatory to welding operations;

Fig. 16 is an external view of the same;

Fig. 17 is a transverse elevational view on line 17—17 of Fig. 1 showing automatically operative shears for severing successive sections of coupled studs;

Figs. 18 and 19 are, respectively, transverse sectional views of the shearing mechanism on lines 18—18 and 19—19 of Fig. 17;

Fig. 19A is a longitudinal sectional view of a plug valve typical of valves employed in the hydraulic operating mechanism for feeding the work to successive operating positions;

Fig. 19B is a diagram indicating different positions of the pieces of work in a complete operating cycle;

Figs. 20 and 21 are, respectively, end elevational views of the strut or spacer feed mechanism on lines 20—20 and 21—21 of Fig. 2;

Fig. 22 is a transverse elevational view of the spacer shear mechanism on line 22—22 of Fig. 2;

Fig. 23 is another transverse view of the spacer shear as seen in the direction of arrow 23 in Fig. 2;

Fig. 24 is a plan view of the spacer feed mechanism on line 24—24 of Fig. 2;

Fig. 25 is an elevational view of the same on line 25—25 of Fig. 2;

Fig. 26 is a plan view of the spacer feed mechanism as viewed in the direction of arrow 26 in Fig. 2;

Fig. 27 is a diagram of the hydraulic system;

Fig. 28 is an electric circuit diagram showing all controls and interconnections;

Fig. 29 is a diagram showing air operated controls and interconnections;

Fig. 30 is a plan view of a section of stud fabricated by the method and means of my invention;

Fig. 31 is a perspective view of a section of fabricated reinforcing panel with studs produced by the means of this invention incorporated therein;

Fig. 32 is a cross sectional view of a stud on line 32—32 of Fig. 30.

A machine for producing fabricated units of the character herein disclosed includes a suitable frame F on which, as viewed in Fig. 1 and progressing from right to left, are mounted a wire straightening unit A, a primary wire feeding unit B, a forming unit C, a welding unit D, and a primary shearing unit E. Also, mounted on frame F, as shown in Fig. 2, there are provided a secondary wire straightening unit G, a feeding unit H, a secondary shearing unit J and an air operated mechanism K for feeding severed spacers in succession to the welding unit D.

The primary feeding unit is arranged to feed wires W, previously straightened by the unit A and feed from reels (not shown) rearwardly of unit A in the same horizontal plane, while the pair of wires are transversely spaced apart, into successive positions relative to units C, D and E, and thence, following completion of each operating cycle, to discharge the completed studs from the machine for further disposition.

The secondary feeding unit H similarly feeds a single wire W' to the shearing unit J where short sections of the wire are severed and, by means of unit K, are delivered to transverse positions between two wires W while they are supported in the welding unit D. Thus, as will hereinafter appear, fabricated studs S of the form shown in Fig. 30 will be formed with parallel longitudinal rods S₁, S₁ and transverse spacers S₂, S₂, etc., at regularly spaced inter-

vals, recessed at points S₃ adjacent the ends of spacers S₂ and welded at the junction points S₄.

Inasmuch as it is both desirable and economical, the studs S including their rods S₁ and spacers S₂ are formed of wire, of preferably three-eighths of an inch cross sectional diameter, and as the two strands of wire W, W are payed out from reels (not shown), straightening of the wires is expeditiously effected by the unit A by the employment of separate straightening elements for the wires.

Unit A includes two groups of peripherally grooved rollers A₁ and A₂ disposed horizontally with one set of rollers on one side and the other set on an opposite of each wire W and similarly rotatable on a bed A₃ of frame F on pins or bolts A₄, A₄, etc. Unit A also includes two groups of peripherally grooved rollers A₅ and A₆ respectively below and above each wire W and carried by a base A₇ on pins or bolts A₈. As shown in Figs. 3 and 4, the rollers A₁—A₂ and A₅—A₆ are staggered in positions and are arranged tandem fashion so as to align the grooves of all of the grooves of all sets of rollers with the operative positions of wires W in units B, C, D and E.

The primary wire feeding unit B (in Fig. 5) includes a horizontal cylinder B₁ supported on end brackets B₂, B₂, a piston B₃ slideable in the cylinder and having a forwardly extended stem B₄ which is fixed to a cross head B₅ bearing a pair of collets B₆, B₆ for receiving the parallel wires W, W. Each of said collets has a frictional gripping device B₇ (Fig. 7) which engages a wire W to move the wire forwardly but permits retraction of the collet on the wire preparatory to a subsequent forward movement of the wire. Said gripping device includes a free rolling pin B₈ movable in an inclined slot B₉ of each collet body and urged into gripping position on a wire W by a bifurcated arm B₁₀ which rocks on an anchor screw B₁₁ borne by the collet and is tensioned by a compression spring B₁₂, as shown in Fig. 7.

The pair of collets B₆ are transversely adjustable on cross head B₅ as by providing reduced portions B₁₃ on the collets which are extended through an elongated slot B₁₄ in cross head B₅ and may be held in adjusted position by nuts B₁₅. The spacing of the collets corresponds to the spacing of the wires W, W for forming the studs S (Fig. 30) of desired width.

Cross head B₅ has hubs B₁₆, B₁₆ which are fixed to parallel horizontal rods B₁₇, B₁₇, respectively, as the ram B₃ is alternately advanced and retracted, and to such end the cross head is fixed at a hub B₁₇ to stem B₄ of the ram. Rods B₁₇ are slidably supported on spaced fixtures B₁₈, B₁₈.

A pair of control valves B₁₉ and B₂₀ are mounted adjacent the front and rear ends, respectively, of cylinder B₁ and are arranged to receive fluid from a source through inlet tubes B₂₁ and B₂₂, respectively. Said valves are connected with the front and rear ends of cylinder B₁ by pipes B₂₃ and B₂₄ and fittings B₂₅ and B₂₆, respectively, and said fittings have exhaust tubes B₂₇ and B₂₈ leading therefrom back to a reservoir of fluid.

Valves B₁₉ and B₂₀ are operated alternately by means of a rod B₂₉ which is actuated by cross head B₅ as it approaches the forward and rearward limit of its stroke. Rod B₂₉ is slideable in supports B₃₀ and B₃₁ which are suitably mounted

on the bodies of valves B_{19} and B_{20} , respectively, and also slides in a slot B_{32} of cross head B_5 . Rod B_{29} carries arms B_{33} and B_{34} adjustable thereon for engagement with the valve stems B_{35} and B_{36} , and also at its forward end has an adjustable nut B_{37} whereby the valves are actuated by rod B_{29} as cross head B_5 reciprocates, for applying fluid pressure to ram B_3 in opposite directions. For example, when ram B_3 and cross head B_5 are completely retracted, valve B_{19} is closed by engagement of arm B_{33} with stem B_{35} while valve B_{20} is opened to permit application of fluid pressure therethrough to the rear side of ram B_3 , thereby forcing the ram B_3 and cross head B_5 forwardly. As the ram nears the end of its forward stroke, cross head B_5 engages nut B_{37} , forces rod B_{29} forwardly, opens valve B_{19} and by engagement of arm B_{34} with stem B_{36} , closes valve B_{20} , thereby reversing the stroke of the ram and cross head. As the ram moves forwardly, the fluid ahead of the ram in cylinder B_1 is exhausted through fitting B_{25} and tube B_{27} . Similarly as the ram moves rearwardly in its cylinder, the fluid behind the ram is exhausted through fitting B_{26} and tube B_{28} .

Thus, the gripping devices B_7 on the collets B_6 simultaneously grip and advance the two parallel wires W, W to initial "joggle" position between the forming dies of unit C or therebeyond to a desired extent and thereafter and successively in step-by-step movements from one position to another to a predetermined extent as controlled by the stroke on the ram B_3 . Certain electrical switches and actuating elements therefor are associated with the valves B_{19} and B_{20} which will be hereinafter described in detail with reference to the circuit diagram shown in Fig. 28 and the compressed air and hydraulic systems shown in Figs. 29 and 27, respectively.

Referring now to Figs. 8, 9 and 10, I will describe the hydraulically operated die forming unit C which is accomplished at the initial position for operation on the work and is effective for providing recesses in the stud wires S_1, S_1 at opposite points on the wires W, W in a single operation of the die unit.

Unit C (Fig. 10) includes a fixed central die member C_1 and relatively movable die members C_2 and C_3 . Member C_1 has similar outer recessed faces and members C_2 and C_3 have similar beaded faces between which the recessed faces of member C_1 the pair of wires W, W are adapted to be extended preceding each forming operation for providing the recesses S_3 in the studs S (Fig. 30). All of the die members may include one or more blocks or plates, one or more of which may be removed or added to properly position the die faces to correspond to the space between wires W, W and the width of studs S .

The die unit is mounted on transversely spaced brackets C_5, C_6 bolted to frame F and cross connected by top rail or rails C_6 and a lower rail C_7 . Rails C_7 have horizontal slots C_8, C_9 through wires W, W extend in the horizontal plane of the collets B_6, B_6 , and the fixed die member C_1 is borne by rails C_7 and secured by bolts C_9 .

The movable die members C_2 and C_3 are secured to blocks C_6 and C_10 , respectively, which are in turn fixed to horizontal plungers C_{11} and C_{12} . One or more spacer blocks C_{13} of the same or different thickness are carried by said plungers, the number and thickness of which is influenced by the size of the central die member C_1 and the spacing of wires W, W .

The plungers are similarly and simultaneously

operated, each by a hydraulic ram C_{14} including a piston (not shown) with an extended stem C_{15} which is commonly pivoted at C_{16} to adjacent ends of a pair of toggle links C_{17} and C_{18} while the inner ends of links C_{18} are pivoted at C_{19} to plungers C_{11} and C_{12} , respectively, and the outer ends of links C_{17}, C_{17} are pivoted at C_{20} to the extended end portions of rails C_7 .

Each ram C_{14} is pivoted at C_{21} to a stationary portion C_{22} of frame F so that the ram may swing slightly during the opening and closing of the toggles. Each ram has an upper fluid inlet C_{23} and a lower inlet C_{24} arranged for connection with a fluid source so that as fluid is delivered to the rams under pressure through inlets C_{24} , the pistons thereof will raise in their cylinders, close the toggles $C_{17}-C_{18}$ and force the plungers C_{11} and C_{12} inwardly with the movable die members and bend the wires W, W while said wires are confined between the stationary die member and the movable die members and thereby provide the recesses S_3 of studs S .

When fluid is admitted to the rams through inlets C_{23} , the pistons are lowered in their cylinders, the toggle joints are broken and the plungers and associated die members are retracted preparatory for a succeeding operation.

The flow of fluid to the rams C_{14} is regulated by electrically actuated valves and the operation thereof will be described with reference to Figs. 27 and 28 hereinafter.

The ensuing operation upon wires W, W follows the cutting and delivery of short sections of a third strand of wire which is fed laterally into the machine and said sections are dropped individually into position in the welding unit D for simultaneously welding the ends of said sections to the wires W, W .

Inasmuch as at the time of a welding operation a short section S_2 has been previously cut from a wire W' and delivered to unit D before continuing with a welding operation, the movement of wire W' and delivery to the welding unit will be described, as follows: A group of straightening rollers arranged in staggered sets A_1 and A_2 followed by a second group of rollers A_5 and A_6 , similarly staggered, are provided between which the wire W' is threaded for straightening the wire in alignment with a hollow stem H_1 of a piston (not shown) which reciprocates in a cylinder H_2 of a hydraulically operable feeding unit H which is supported on spaced brackets H_5, H_5 secured to frame F . Wire W' is extended entirely through stem H_1 and is gripped by a collet H_3 bearing a gripping device H_4 of the character of that shown in Fig. 7 and employed on collets B_6 of the primary dual wire feeding unit E . Opposite ends of cylinder H_2 are supplied with fluid through inlets H_6 and H_7 leading from valves H_8 and H_9 , respectively, said valves being connected with a source of fluid by means of pipes H_{10} and H_{11} , respectively. Valves H_8 and H_9 are electrically actuated as hereinafter described, but primarily through the reciprocation of an actuating rod H_{10} which is slidable on supports H_5, H_5 and is slidable moved by means of an arm H_{12} fixed to stem H_1 , and alternately engageable with spaced nuts H_{13} and H_{14} on rod H_{10} (Fig. 26).

The feeding unit H thus advances wire W' in the direction of the welding unit D in step-by-step movements so that successive sections of the wire will be presented for cutting spacer sections S_2 by means of the shearing unit J which is shown in Figs. 2, 22 and 23. Said shearing unit includes a mounting J_1 secured to frame F , a ram J_2 hinged

at J_3 to said mounting and pivotally secured to a crank arm J_4 which in turn is pivotally carried on mounting J_1 . Ram J_2 is tensioned by a spring J' secured to frame F .

A stationary blade J_5 is secured to mounting J_1 as by means of bolts J_6 and a movable blade J_7 is slidably supported on the mounting for movement over the face of blade J_5 . Blade J_5 is pierced to permit extension of wire W' therethrough and blade J_7 has an elongated radial slot J_8 therein to accommodate the movement of an eccentric crank pin J_9 carried on the heel of arm J_4 . Thus, at each operating thrust of the stem J_{10} of ram J_2 , arm J_4 is swung downwardly as viewed in Fig. 23 and blade J_7 is moved to the right so that its cutting edge engages wire W' and shears off a section of wire to form a strut or spacer S_2 . A strut holder J_{11} is provided forwardly of the shearing blades for temporarily holding the severed struts (Fig. 25) until they are ejected in a succeeding operation by engagement of the front end of wire W' therewith, as and for the purpose hereinafter explained. The connections of ram J_2 with the hydraulic system and the electrical controls for the fluid valves will be described in connection with the hydraulic and electrical diagrams of Figs. 27 and 28, respectively.

In Figs. 24 and 25 I have shown a mechanism K for receiving and transferring the severed struts S_2 from the shearing unit J to the welding unit D . Unit K includes a frame K_1 with a compressed air cylinder K_2 mounted thereon and provided with air inlets K_3 and K_4 at opposite sides of a piston (not shown) and through the inner end of which a hollow piston stem K_5 extends. Frame K_1 supports a trio of parallel rods K_6 connected at their forward ends by a bar K_7 , for slidably supporting a strut transfer tray K_8 in a plane such that the longitudinal groove K_9 on its upper side will at times align with struts S_2 as they are ejected from the holder J_{11} of the shearing unit J . Rods K_6 slidably receive sleeves K_{11} of tray K_8 and limit the outward thrust of the tray K_8 by engagement with stops K_{10} borne by rods K_6 to a position of alignment with holder J_{11} as illustrated in Fig. 25, while the retractive movement thereof is limited by engagement with a rear flange of frame K_1 , or otherwise.

Piston stem K_5 is secured to a depending lug K_{12} of tray K_8 and thus serves to move the tray between positions of alignment with holder J_{11} and an elongated tube K_{13} which extends transversely on frame F from frame K_1 to a point adjacent the welding unit D . Hence, as a strut is ejected from holder J_{11} upon tray K_8 , said tray is shifted from strut receiving position to strut ejecting position in registration with tube K_{13} by means of the compressed air unit K_2 and a blast of air is directed against the trailing end of the strut under control of a solenoid actuated valve K_{14} from an air outlet K_{15} which is in axial alignment with the strut and with tube K_{13} . The blast of air is of sufficient force and duration to eject the strut from the tray K_8 into and drive the same completely through tube K_{13} and thence therefrom into a dropping unit L (Figs. 15 and 16) which is mounted slightly above the welding unit D .

The leading end of the strut delivery tube K_{13} opens into an end of an elongatedly channelled receiver L_1 which is adjustably mounted on a stationary plate of frame F as by means of one or more screws and is arranged with a pair of parallel detents L_5 and L_6 having longitudinally disposed bodies of arcuate cross section and mounted

one above the other (Figs. 15 and 16). Said detents are pivotally mounted on the opposite ends of member L_1 on trunnions L_7 and L_8 , respectively, and are connected for simultaneous rotation in opposite directions by gears L_9 and L_{10} fixed to adjacent arms L_{11} and L_{12} at the opposite ends of members L_5 and L_6 (Fig. 16). A central arm L_{13} extends from member L_5 and is pivoted at L_{14} to a piston stem L_{15} extended from a

10 piston (not shown) of a compressed air operating unit L_{16} which is electrically operated by a solenoid L_{17} for dropping successive struts in single file procession into welding position and restraining a second strut from dropping out of turn.

15 A strut delivered from tube K_{13} is ejected endwise into the channel of member L_1 and temporarily rests upon the upper detent L_5 until detent L_5 is retracted by the downward thrust of stem L_{15} , but as detent L_5 is retracted, the lower detent L_6 is extended inwardly to a position beneath the then released strut which is thereby prevented from dropping into welding position. A retractive movement of stem L_{15} again moves the detent L_5 into position for receiving a succeeding strut from tube K_{13} while detent L_6 is retracted and permits the dropping of the strut then resting upon it into welding position on unit D .

20 The welding unit D , as shown in Figs. 11 to 14 inclusive, includes a pair of transversely aligned electric welders D_1 , D_1 of the character and type shown in Fig. 12. Each welder D_1 is associated with a hydraulic ram D_2 , the piston stem D_3 of which is effective for extending the electrodes D_4 into respective contact with the two wires, W , W which are positioned on a supporting bed D_5 on opposite sides of a central vise composed of a stationary jaw member D_6 and a relatively movable jaw member D_7 (Fig. 13) hinged at D_8 to member D_6 . Thus, while the two wires W , W are longitudinally disposed on the vise, the struts S_2 are dropped from unit L into gripping position between blocks D_8 and D_9 while the jaws D_6 and D_7 are open and are held in a position at right angles to and between the wires W , W .

25 The vise is operated by a hydraulic ram D_{10} , the piston stem of which is pivoted at D_{11} to jaw D_7 and the ram is bodily pivoted at D_{12} on frame F so as to compensate for the pivotal movement of jaw D_7 . Following the closing of the vise with a strut and a pair of wires W , W in properly abutting position thereon, fluid pressure is applied to the welders D_1 , D_1 from rams D_2 , D_2 which receive pressure from a source through tubes D_{13} and the electrodes are thrust into contact with wires W , W and the struts S_2 are butt welded simultaneously to both of said wires. Ram D_{10} receives and exhausts fluid through a tube D_{14} which is connected with a source of fluid under pressure.

30 The rams D_2 , D_2 are stationarily supported on brackets D_{15} , D_{15} while the welders D_1 , D_1 are movably supported on bearings D_{16} , D_{16} and are bodily slideable with their electrodes D_4 into and from welding positions. Each welder D_1 includes a tip holder D_{17} held in a sleeve D_{18} and secured thereto as by means of a screw D_{19} . Sleeve D_{18} is insulated from holder D_{17} by an insulating sleeve D_{20} and is similarly insulated by a disc D_{21} between the trailing end of the holder and a sleeve closure D_{22} which is welded to sleeve D_{18} and is connected with the piston stem of ram D_2 by means of an adaptor D_{23} so as to effect bodily movement of the welder when the piston is reciprocated. Pref-

erably sleeve D₁₈ is keyed to the leading bracket D₁₅ by a key D₂₄ operating in an elongated slot D₂₅ of sleeve D₁₈, so as to prevent rotation of said sleeve in its supporting brackets.

Holder D₁₇ is axially bored at D₂₆ and counter-bored on a taper at D₂₇ for receiving an electrode D₄ which is correspondingly tapered and removably seats in counterbore D₂₇. A water tube D₃₈ is screwed into a tapped hole at the trailing end of holder D₁₇ and extends axially through bore D₂₆ and into a bore D₂₉ of electrode D₄ so that water from a radial inlet D₃₀ may circulate through the tube and bores D₂₆, D₂₇ and D₂₉ and thence outwardly through an outlet D₃₁ in a jumper terminal D₃₂. Said terminal has threaded contact with holder D₁₇ and a cable D₃₃ leads therefrom with a flexible insulated sheath D₃₄ to an output terminal of a transformer T by means of which electric current of desired potential different from that of a service system is supplied to and through the two electrodes D₄, D₄ for providing a welding arc at a point of welding the struts S₂ to the pair of wires W, W. Usually, a welding control unit T' of conventional form and character is electrically connected with the transformer T for purposes well known in the arc welding art and hence will not be herein described in detail. Thus, as current flows from one terminal D₃₂ to the other, through the electrodes D₄, D₄, the metal bodies between the electrodes are fused and the parts thereof permanently welded together. The welders D₁, D₁ are continuously cooled by the circulation of water therethrough.

The wires W, W forming the longitudinal members S₁, S₁ of studs S are simultaneously cut by means of a special shearing apparatus E mounted at the output end of frame F and includes separate cooperating units E₁, E₁ formed of identical parts and similarly arranged. Each unit E₁ is mounted on a bracket E₂ fixed to the bed of frame F and includes a ram E₃ which is pivotally held at E₄ to swing on the upper extremity of mounting E₂ and the extended stem E₅ of its piston (not shown) in hinged at E₆ to a crank E₇ which is oscillatably held on mounting E₂ on a shaft E₈. The weight of units E₁ is relieved by tension springs e which are suspended from frame F.

A pair of mating cutting jaws E₉ and E₁₀ are formed at the inner ends of levers E₁₁ and E₁₂, respectively, of each unit E₁ and are pivotally mounted at points E₁₃ and E₁₄, respectively, on mounting E₂. The jaws E₉ and E₁₀ are so disposed that they will engage opposite points on the wires W, W. The lower arms E₁₂ rest upon stop pins E₁₅ at the bottoms of yokes E₁₆ and are so held by tension springs E₁₇ which are anchored to fixed arms E₁₈ extended inwardly from mountings E₂ and the upper ends of said springs are attached to arms E₁₂. Similar springs serve to retract the upper jaws E₉ upwardly. Yokes E₁₆ have straps E₁₉ bored to embrace eccentric discs E₂₀ formed on shafts E₈ and said discs are connected by eccentric pins E₂₁. The eccentric pins E₂₁ bear against and depress the arms E₁₂ while the discs E₂₀, through straps E₁₉ both raise and lower the arms E₁₂ as the rams E₃ operate. Thus, in a cutting operation, the jaws E₉ and E₁₀ which are normally open are moved toward each other until completion of cuts in wires W, W. The thrust of piston stems E₅ is limited and cushioned by means of pairs of parallel rods E₂₂, E₂₂, on each mounting E₂ which are cross connected at their inner ends by bars E₂₃. Said rods E₂₂ are supported in sleeves E₂₄ fixed to mountings E₂ and carry cush-

ioning springs E₂₅, E₂₅ which compress between said sleeves and nuts E₂₆, E₂₆ on said rods.

Each cycle of operation from "home" position includes a series of steps effected under control

- 5 of a stepping switch to final position and a new cycle begins each time the main feed unit B moves the wires W, W to the extent of one bay (sixteen inches preferably) during which all of the units of the mechanism are operated in succession or in turn, except the main shearing unit E which operates selectively upon the completion of a predetermined number of cycles and the welding of a corresponding number of spacers S₂ to said wires. Let it be understood that when 10 the mechanism is under "home" conditions, all of the units are at rest and retracted in readiness for a succeeding cycle of operations. When the main feed unit B moves forwardly at the beginning of the first step in a cycle, the collets 15 B₆, B₆ grip the pair of wires W, W and move them to a predetermined extent at the initial and all subsequent operations, but prior to an initial operation thereof, the wires W, W will have been first manually threaded through the 20 straightening unit A and to a point slightly beyond the forming unit C and the forming unit C also manually operated by closing a suitable electric switch to be hereinafter described, thereby positioning the wires W, W for automatic and 25 successive uniform step-by-step movements.

In the meantime, the spacer feed wire unit H will have been independently and manually operated for advancing a cut spacer to position the welder unit D, during which advance the wire W' 30 will have been threaded through the straightener unit G, the strut feed unit H and automatically through the shearing unit J and a cut spacer delivered by unit K to the dropper unit L for deposit upon the welder between the then open 35 jaws D₈ and D₉.

Shortly after the beginning of the initial forward movement of the collet bearing cross head B₅ of unit B, the rods B₁₇, B₁₇ engage separate actuators of micro-switches mounted on frame F, 40 and thereby, respectively, close the circuit of the strut dropping unit L and thus drop a then present spacer into position between the jaws D₈ and D₉ of the welder D, and close the jaws D₈ and D₉ on the spacer, thus completing the first step.

The distance between the forming unit C and the welder D is the same as that between the spacers S₂ of panel P (sixteen inches), hence, while the initially formed portions S₄, S₄ of wire W, W are still held in the vise D₈—D₉ of the 45 welder and following the deposit of a spacer S₂ between portions S₄, S₄, a succeeding operation of unit C begins a second step for providing similar portions S₄ in the wires W, W at a distance from the first formed portions which is equal to 50 the distance between the units C and D.

Coincidentally with the operation of unit C, the main feed element B₅ and dropping unit L are retracted. At the final operation of each step, the stepping switch M is actuated for initiating a succeeding step, hence at this point (and subsequently) the stepping switch is actuated, as hereinafter explained, to institute step three which begins with the operation of welder D and the inward thrust of the electrodes D₃, D₃ into contact with portions S₄, S₄ of wires W, W which, together with a spacer S₃, is still held in the vise D₈—D₉ of the welder, and simultaneously therewith, the feed unit H advances and deposits a spacer in the transfer tray K₉ of unit 65 K. At the completion of the feed stroke and a

welding operation, the stepping switch is again actuated, this time by the approach of stem H_1 to the end of its stroke and actuation thereby of a micro-switch preparatory to a fourth step.

Step 4 then ensues and is automatically operative for retracting main feed cross head B_5 , the forming die members C_2 and C_3 , the electrodes D_3 , D_3 of the welder D and the spacer clamping jaws D_8 and D_9 . Simultaneously therewith, the spacer transfer blower K_{15} is operative for transferring a spacer S_3 from tray K_9 through delivery tube K_{13} to position in the dropper L onto the upper detent L_5 (Fig. 13) from which it may be subsequently dropped to position between the welder clamping jaws D_8 and D_9 , as before.

At this point in the operation of the machine, one cycle of operation will have been completed under the control of a cycle stepping switch M in step-by-step sub-operations while the pre-selected number of cycles necessary to produce studs of given length (numbers of spacers and intermediate bays) is controlled by a selector stepping switch M' which is arranged to be manually set for any desired number of cycles. When, for instance, the selector stepping switch has been set for producing studs S of 15 bays and 16 spacers at the completion of each step of a cycle, the cycle stepping switch will advance one point and at the end of the fourth step will return to "home" position. At the completion of each cycle, the selector stepping switch will advance one point and at the completion of the sixteenth cycle, will return to "home" position.

The fifth step in a cycle is occasioned only after completion of the fourth step in a final cycle and is effective only for operating the shearing unit E for severing a completed stud from the wires W , W . At the end of a shearing operation, micro-switches are actuated for retracting the shears and when the shearing elements E_1 approach completely retracted positions, electrical contacts are made which effect the "hom-ing" of both the cycle and selector stepping switches.

Whereupon, after the severing of each complete stud S , both stepping switches are automatically operative for another series of cycles for producing successive studs S of uniform and predetermined length from the continuous wires W , W and the cut spacers S_3 .

The units of the machine are operated by mechanical, hydraulic, pneumatic or electrical means, or combinations thereof. For example, certain units are controlled by electrically actuated valves for regulation of fluid pressure (air or liquid) to the power media, other units solely by valve actuated electric switches, and still other units by combinations of solenoid operated valves and valve actuated switches, all of which are disclosed in the drawings and will be hereinafter explained in detail with particular reference to Figs. 27, 28 and 29 which show, respectively, the hydraulic system, the electrical system and the compressed air system.

It may be understood that well known hydraulic, electric and pneumatic parts, fittings and devices are employed in all of said operating systems and are not shown and will not be described herein in detail because their functions are well known.

Referring first to Fig. 27, I will describe the hydraulic system. Water or other liquid is drawn from a reservoir or settling tank through a pipe 2 by and through a pump 3 , thence forced through a pressure line 4 to and through a pres-

sure regulator 5 for maintaining a desired uniform pressure and back to the tank 1 through a pipe 6 . All of the units B , C , D , E , H and J receive pressure from pipe 4 and exhaust the fluid either directly or indirectly through branches to pipe 6 , as follows:

Fittings B_{25} and B_{26} of unit B receive fluid through branch pipes B_{21} and B_{22} , respectively and discharge the fluid through pipes B_{27} and B_{28} connected with a secondary return pipe 7 , pipes B_{21} and B_{22} having solenoid controlled valves V_1 and V_2 connected therewith between pipe 4 and valves B_{19} and B_{20} , respectively. Pipes B_{27} and B_{28} have similar solenoid controlled valves V_3 and V_4 connected therewith between fittings B_{23} and B_{24} , respectively and pipe 7 .

Cylinders C_{14} , C_{14} of unit C are each supplied with fluid at corresponding ends through pipes C_{25} , C_{25} connecting inlets C_{23} , C_{23} with a common pipe C_{28} having a fitting C_{27} connecting pipe C_{26} with pressure pipe 4 through a pipe C_{28} and also with exhaust pipe 7 through a pipe C_{29} . Solenoid controlled valves V_5 and V_6 are connected with C_{28} and C_{29} , respectively, between fitting C_{27} and pipes 4 and 7 . Similarly, the corresponding other inlets C_{24} , C_{24} of cylinders C_{14} , C_{14} are commonly connected with a pipe C_{30} which has a fitting C_{31} commonly connected with pipes C_{32} and C_{33} leading to pipes 4 and 7 , respectively. Solenoid operated valves V_7 and V_8 are connected with pipes C_{32} and C_{33} , respectively, between fitting C_{31} and pipes 4 and 7 .

Cylinder D_{10} of unit D receives fluid at its single inlet D_{14} from a fitting D_{35} which is commonly connected with pipes D_{36} and D_{37} leading, respectively, to pipes 4 and 7 and having solenoid valves V_9 and V_{10} connected therewith between fitting D_{35} and pipes 4 and 7 .

Cylinders D_2 , D_2 of unit D have their inlets D_{13} , D_{13} commonly connected with a fitting D_{38} , a connecting pipe D_{39} and thence with pipes 4 and 7 by similar pipes D_{40} , D_{40} and solenoid controlled valves V_{11} and V_{12} are connected with pipes D_{40} , D_{40} , respectively.

Cylinders E_3 , E_3 , of unit E have inlet pipes E_{27} , E_{27} commonly connected with a fitting E_{28} and a short pipe E_{29} and thence through similar pipes E_{30} and E_{31} with pipes 4 and 7 but through solenoid operated valves V_{13} and V_{14} .

Inlet pipes H_{10} and H_{11} of unit H are connected through solenoid operated valves V_{15} and V_{16} and H_{15} and H_{16} , respectively, with pressure pipe 4 and at points between valves H_8 and H_9 and cylinder H_2 , said cylinder being connected with exhaust pipe 6 by pipes H_{17} and H_{18} through solenoid operated valves V_{17} and V_{18} , respectively.

Cylinder J_2 of unit J has its common inlet and outlet J_{12} connected at J_{13} , through pipes J_{14} and J_{15} and solenoid operated valves V_{19} and V_{20} , with pipes 4 and 6 . Thus, with pipe 7 connected at 8 to pipe 6 , fluid fed to the several units from tank 1 by pump 3 , through pressure line 4 , is exhausted into the main return pipe 6 , all under control of the solenoid operated valves generally indicated at V on the drawing and of like character and arrangement, but otherwise individually identified in the preceding description.

The strut transfer unit K and delivery or dropper unit L are, as shown in Fig. 29, connected with and are adapted for pneumatic operation through the medium of a compressed air system including a pressure line 10 arranged for connection with a compressor or other source (not shown). Unit K , which is effective for laterally transferring a cut spacer from the shearing unit

J to position for projection through tube K₁₃ to the dropper unit L, has its cylinder K₂ provided with inlet tubes K₁₄ and K₁₅ at its opposite extremities and said inlet tubes are connected through valves K₁₆ and K₁₇, respectively, and pipes K₁₈ and K₁₉ with pressure line 10. Said valves K₁₆ and K₁₇ are adapted for operation with the ram of unit H as it approaches opposite limits of its stroke and thus serve to control and effect reverse movement of the piston for sliding the tray K₈ between strut receiving and ejecting positions.

Pipe 10 has a manually operable shut-off valve V₂₁ between the source of compressed air and its junction with pipe K₁₉ and a blower pipe K₁₅ leads from pipe 10 and also has a manually operable valve V₂₂ therein and, in addition, a solenoid operated valve V₂₃ near its outlet end whereby the blast of air from pipe K₁₅ is timed and controlled for projecting the cut struts through tube K₁₃ to dropper unit L. Valves K₁₆ and K₁₇ are opened to exhaust by pressure from cylinder K₂ on exhaust strokes of the piston and are of conventional character.

Cylinder L₁₆ of dropper unit L is supplied with pressure from opposite ends through pipes L₁₈ and L₁₉ which are connected with pipe 10 and with solenoid controlled valves V₂₄ and V₂₅, respectively. Pipe L₁₉ is connected at L₂₀ to an exhaust pipe L₂₁ having a solenoid operated valve V₂₆ connected with and for controlling the exhaust from one end of cylinder L₁₆ through pipes L₁₉ and L₂₁, while the exhaust from the opposite end of said cylinder is through a pipe L₂₂ and a solenoid controlled valve V₂₆.

Thus, as air is admitted through pipe L₁₈ under control of valve V₂₄, exhaust valve V₂₆ will be closed and as the piston in the cylinder moves away from the open inlet, air is exhausted through pipes L₁₉ and L₂₁ as valve V₂₆ will then be open and valve V₂₅ will be closed. On a reverse stroke of the piston, air will be admitted through inlet pipe L₁₉ to cylinder L₁₆ as valve V₂₅ will then be open and exhaust valve V₂₆ will be closed. Simultaneously therewith exhaust valve V₂₄ will be open, inlet valve V₂₄ will be closed and air will be exhausted from cylinder L₁₆ through pipe L₂₂ and valve V₂₆ as the piston travels upwardly in its cylinder.

In considering the electrical system shown in the diagram of Fig. 28, it may be understood that in the form of mechanism herein disclosed all of the steps of a cycle are performed by hydraulic, pneumatic or mechanical means except for actuating the stepping switches M and M' and the solenoid controlled valves which are operated electrically. The several steps of a cycle are controlled by mechanically actuated micro-switches or limit switches which are borne by either stationary or movable members and are actuated by engagement of their actuators with a movable or stationary member, respectively, whereby at an appropriate point in the operation of one unit the mechanism will be automatically set to institute or carry out another or succeeding step of a cycle, or reverse the operation of a unit such as the main feed unit B.

The electrical system is also arranged for total automatic or manual operation of its units whereby at any point in a cycle, when the mechanism is set for automatic operation, certain units may be manually operated, as when any step in a cycle may have been incomplete for any reason. For instance, at the beginning of

stud producing operations or if the supply of wire W' should be replenished, the units B, C, D and E could be manually discontinued while the strut producing units H, J, K and L remain operative until a strut is placed in the dropper L or welder D, whereupon automatic operation may be resumed.

To such ends the electrical system shows in Fig. 28 all of the electrical controls except for the welding unit D and are mounted on a single panel being supplied with electric energy through lead in wires M₁ and M₂ and fuses M₃ and M₄ between which and a source a main switch M₅ is connected. A rectifier M₆ is provided for stepping down the current from 110-115 to 24 volts adaptable for energizing certain relays, etc., which will be hereinafter described. Rectifier M₆ is connected by leads M₇ and M₈ from wires M₁ and M₂, respectively.

Line switches M₉ and M₁₀ are connected with wires M₂ and M₁, respectively, switch M₉ having a single pole bar M₁₁ while switch M₁₀ is double pole and has dual contact bars M₁₂ and M₁₃. Switch M₉ is for manual control and switch M₁₀ is for automatic control of operations. Hence, when switch M₉ is open, switch M₁₀ will be closed, and vice versa. Switch M₉ is connected at a terminal m₁₁ by a wire m₁₂ with manually operable snap action toggle switches m₁₃, m₁₄, m₁₅ and m₁₆ through branches M₁₇, M₁₈, M₁₉ and M₂₀, said toggle switches serving to individually control the operation of feed unit B, forming unit C, shearing unit E and retraction of said units, respectively. Switch m₁₃ has a terminal M₂₁ connected with a wire M₂₂ leading to a terminal M₂₃ of the cycle stepping switch M. A branch wire M₂₄ leads from wire M₂₂ and serves as a feeder for energizing the solenoid of and actuating the solenoid controlled valves of successive units B, D and J. A limit switch M₂₅ is normally closed and is connected between wire M₂₄ and valve solenoids V₂ and V₃ whereby both solenoids are controlled by switch M₂₅ which in turn is mechanically opened at the end of a forward stroke of piston B₃ of unit B by engagement of an arm B₃₄ with stem B₃₆ of valve B₂₀ (Fig. 5).

Wire M₂₄ also connects with a normally open limit switch M₂₆ and, in addition, a normally closed limit switch M₂₇ and current is supplied to valve solenoid V₉ through switches M₂₆ and M₂₇, switch M₂₇ being actuated by the upward thrust of cylinder D₁₀ of unit D which operates the spacer clamping jaws D₈ and D₉ (Fig. 13). Switch M₂₆ is closed by one of the cross head rods B₁₇ as it approaches its forwardmost limit of movement but before switch M₂₅ is actuated.

Wire M₂₄ also connects with valve solenoid V₂₀ through a single normally closed limit switch M₂₈ which is borne by cylinder J₂ of spacer shearing unit J and is actuated by engagement with a part of piston stem J₁₀ as shown in Figs. 22 and 23.

Switch m₁₄ has its terminal M₂₉ connected with a wire M₃₀ which parallels wire M₂₂ and has a branch M₃₁ paralleling branch M₂₄ and connected with elements of and for operating forming unit C and spacer feed H. Wire M₃₁ is connected with valve solenoids V₆ and V₇ of unit C through a pair of series connected normally closed limit switches M₃₂ and M₃₃ (Fig. 8) which are actuated by the closing of the forming dies by engagement with C₁₈, C₁₉ for opening the circuits of solenoids V₆ and V₇. Wire M₃₀ extends to a terminal M₃₅ of cycle stepping switch M.

Wire M₃₁ also connects with valve solenoids

V_{16} and V_{17} through a single normally closed limit switch M_{34} which is opened by engagement of arm H_{11} of spacer feed unit H when the piston stem H_1 is at its rearmost position, as shown in Fig. 2.

A terminal M_{36} of switch m_{15} is connected with a wire M_{37} which extends to a terminal M_{38} on cycle stepping switch M and has a branch M_{39} leading to valve solenoid V_{13} of unit E and is connected through a pair of normally closed series connected limit switches M_{40} and M_{41} which are actuated by piston stems E_5 , E_6 of unit E (Fig. 17).

Switch m_{16} has a pair of terminals M_{42} and M_{43} connected with wires M_{44} and M_{45} , respectively. Wire M_{44} leads to a terminal M_{46} of cycle stepping switch M and has a branch M_{47} leading to the main shearing unit E for energizing valve solenoid V_{14} through a pair of normally closed limit switches M_{48} and M_{49} borne by cylinders E_3 , E_3 which are actuated by and when piston stems E_5 , E_6 are retracted from the positions shown in Fig. 17.

Wire M_{45} leads to a terminal M_{50} of cycle stepping switch M and has a branch M_{51} arranged for connection with valve solenoids of units B , C , D and J . Solenoids V_1 and V_4 of unit B are connected through a single normally closed limit switch M_{52} with wire M_{51} . Solenoids V_5 and V_8 are connected with wire M_{51} through a pair of normally closed limit switches M_{53} and M_{54} borne by fixed member C_{21} and actuated by toggle arms C_{18} (Fig. 8).

Valve solenoid V_{12} of unit D is connected with wire M_{51} through a pair of normally closed limit switches M_{55} and M_{56} which are actuated by elements D_1 , D_1 of unit D . Valve solenoid V_{10} of unit D connects with wire M_{51} through a single normally closed limit switch M_{57} .

Valve solenoids V_{19} of unit J and V_{23} of unit K connect with wire M_{51} through a normally closed limit switch M_{58} which is actuated by J_{10} of unit J upon the retraction of said stem.

The circuits of valve solenoids V_2 and V_3 , V_1 and V_4 of unit B ; V_6 and V_7 , V_5 and V_8 of unit C ; V_{12} and V_{10} of unit D ; and V_{13} and V_{14} of unit E , and other valve solenoids as will herein-after appear, all completed by a common power lead M_{59} under the influence of a toggle control switch M_{60} with which wire M_{59} is connected at a terminal M_{61} . Switch M_{60} is arranged to cut out units B , C and D for discontinuing advance of wires W , W while permitting the continued operations of units H , J , K and L as when for any reason it is necessary to synchronize the two groups of units fed by units B and H . A terminal M_{62} of switch M_{60} is connected by M_{63} with main lead M_1 . Thus the circuits of said valve solenoids are completed through switch M_{11} to main lead M_2 and the solenoid and switch connections hereinbefore described for manual operation of the machine.

The valve solenoids V_{24} and V_{27} are commonly fed from lead M_{59} and are connected with a common return lead M_{64} through a normally closed limit switch M_{65} which is actuated by and when the dropper stem L_{16} moves downwardly and a normally open limit switch M_{66} which is actuated by a rod B_{17} of unit B (Figs. 5, 13 and 14). Solenoids V_{25} and V_{26} are also connected with wire M_{64} through a normally closed limit switch M_{67} which is actuated by and upon retraction of the dropper.

Wire M_{64} leads from a terminal M_{68} of a toggle switch M_{69} thence through wire M_{70} to wire M_{24} and completes the circuit of elements V_{24} , V_{25} ,

V_{26} and V_{27} through a return wire M_{59} leading to and connected with switch M_{60} . Switch M_{60} , however, is closed only when the machine is set for automatic operation. Wire M_{64} is connected by a wire m_{20} with wire M_{20} to switch m_{16} for retracting the spacer dropper.

Valve solenoid V_{11} of unit D connects with wires M_{71} and M_{72} . Wire M_{71} leads to a point of connection with a wire M_{73} which connects a pair of relays R and R' associated with the welder control circuit and under the influence of a conventional weld timer contactor unit D' . Wire M_{72} leads to a point of connection M_{74} with a wire M_{75} having a branch connected with step three terminal M_{76} on the cycle stepping switch and is extended from said branch to and is connected by leads M_{77} and M_{78} to relays R and R' , respectively.

Valve solenoid V_9 connects with wire M_{71} and through switches M_{27} and M_{28} with wire M_{24} .

10 A lead wire M_{79} extends from terminal M_{80} of switch M_{10} to and for connection with elements of units H , K and J as follows: Valve solenoids V_{15} and V_{18} connect with wire M_{81} and through 15 a normally closed limit switch M_{82} with wire M_{72} and thence to cycle stepping switch M and relays R and R' .

20 Valve solenoids V_{16} and V_{17} of unit H connect with wire M_{79} and through switch M_{34} with wire M_{31} .

25 Valve solenoids of V_{19} of unit J and V_{23} of unit K connect with wire M_{79} and through switch M_{83} with wire M_{51} .

30 Valve solenoid V_{20} of unit J connects with wire M_{79} and through switch M_{28} with wire M_{24} .

35 As is customary, a conventional transformer T (Fig. 1) and a weld timer contactor unit D' of conventional character (Figs. 1 and 28) are associated with the welding unit D and operatively connected, as shown in Fig. 28, for controlling the electrical operation of the welding unit. The electric energy employed for welding the struts to the wires W , W is of a potential of 440 volts from transformer T direct to the two electrodes D_4 , D_4 through conductors D_{31} , D_{31} , the circuit being completed through said conductors, said electrodes and the interposed work and output terminals of the transformer (not shown). Contactor unit D' operates on a potential of 115 volts as serves the purpose of timing the welding intervals, as is well known in the welding art.

40 Wires M_{83} and M_{84} lead from unit D' to terminals M_{85} and M_{86} , respectively, of double coil relay R' for supplying energy to one of its coils while wires M_{78} and M_{87} connect with terminals M_{88} and M_{89} , respectively, of its other coil.

45 It may be understood that the welding circuit is substantially standard and includes well known units for controlling the application of energy to the welding electrodes and is not, therefore, in such respects a part of this invention. Also, the controls for synchronizing the welder with the other units of the machine in order to keep the welding unit in step with the other units, while operating automatically, include the relays R and R' connected as shown, or otherwise, with the welding unit with the stepping switches through wires M_{75} and M_{77} to relay R and thence through wires M_{73} and M_{87} to relay R' . By reason of said connections, when cycle stepping switch M advances to third position, the circuit of relay R is closed and current flows from terminal M_{76} of switch M through wires M_{75} , M_{72} , solenoid V_{11} , wire M_{71} , M_{73} , relay R , armature r , thereby completing the welding circuit composed of wires M_{80} and M_{81} which lead to a welding

circuit control unit (not shown), but conventionally connected with unit D'. Then energy is supplied to relay R' through wires M₈₃ and M₈₄, thereby closing armature switch r' and through a wire M₉₂, and switch M₆₀, wire M₉₃ and switch M₁₀ to power line M₁, thence through wire M₇₁ to solenoid V₁₁. Thus, through operation of solenoid V₁₁, fluid is supplied to cylinders D₂, D₂ of unit D which extends the electrodes D₄, D₄ into operative position on the work. When cycle stepping switch M again moves to the fourth and final step of each cycle, the circuit of relays R and R' are opened and all units retract in readiness for a succeeding cycle.

Usually, switches M and M' are arranged with banks of arcuate contacts and common concentric rotatable wipers for consecutive operations of desired number for making and breaking the circuits of different units.

For instance, the row of terminals of switch M including M₃₅, M₃₈, M₂₃, M₄₆, etc., and a parallel row of contacts M₄₄, M₉₄, etc., are correspondingly arranged and adapted to be bridged by a wiper. Similarly, two rows of contacts M₉₅, M₉₅, etc., and M₉₆, M₉₆, etc., are likewise bridged by a wiper for operating the units in sequence, step-by-step in each cycle.

The selector stepping switch M' has parallel rows of bridged contacts M₉₇—M₉₈ and M₉₉—M₁₀₀ and M₁₀₁—M₁₀₂ while a manually operable selector M₁₀₃ has bridged rows of contacts M₁₀₄—M₁₀₅ and corresponding connections M₁₀₆, M₁₀₆, etc., between contacts M₁₀₂ and M₁₀₄. The number of contacts in each row of switch M' is influenced by the number of steps in each cycle and the number of contacts in each row of switch M' is influenced by the maximum number of cycles in each stud making operation. As shown, each cycle includes four steps except the final cycle which has a fifth step for cutting off a completed stud having sixteen struts and fifteen bays, hence each switch M and selector M₁₀₃ has contacts for sixteen cycles.

The bank of contacts M₉₄ commonly connect by a wire M₁₀₇ with a terminal M₁₀₈ of an electronic relay unit M₁₀₉ while the bank of contacts M₉₅ commonly connect by a wire M₁₁₀ with a homing relay R₁ and therethrough by a wire M₁₁₁ with an armature switch M₁₁₂ which closes the circuit of a wire M₁₁₃ commonly connected with the bank of contacts M₁₀₅ of selector M₁₀₃.

The bank of contacts M₉₆ of switch M are commonly connected by a wire M₁₁₄ first with a stepping relay M₁₁₅ and a homing relay M₁₁₆ in sequence, then by a branch M₁₁₇ with a stepping relay R₂, thence through said relay by a wire M₁₁₈ with the bank of contacts M₉₇ of switch M'. Wire M₁₁₄ leads to one terminal of rectifier M₆ while another wire M₁₁₉ leads from the rectifier to and through relay R₁ and thence to wire M₁₁₀, thereby completing the circuit of relay R₁ and through wire M₁₁₀ connects with the bank of selector contacts M₁₀₀.

Relay R₂ connects by wire M₁₂₀ through wire M₁₁₈ with contact bank M₉₇ and when energized, its armature r₂ closes a line M₁₂₁ leading back to line M₁₁₄. A single toggle switch m₁₂₁ adapted for manually operating the stepping switches M and M' has a connection M₁₂₂ with an armature switch r₄ actuated by relay R₂ and through the switch m₁₂₁ has a line M₁₂₃ leading to an armature switch r₅ actuated by relay R₁ for controlling the interconnection between relay R₁, switch m₁₂₁ and a double toggle switch M₁₂₄ which is man-

ually operable for having both stepping switches M and M'. To such end, switch M₁₂₄ is connected at M₁₂₅ with wire M₁₂₀ and by wire M₁₂₆ and armature switches r₂ with switch M₁₂₁ through wire M₁₂₃, stepping relay M₁₁₅ with wire M₁₂₃ and homing relay M₁₁₆ connects with wire M₁₂₅.

Wire M₁₁₄ connects by wire M₁₂₆ with a relay M₁₂₇ of selector switch M' and by a wire M₁₂₈ with contacts M₁₀₁ under control of an interposed switch M₁₂₉ in line M₁₂₈. Certain contacts M₉₅ of switch M are connected with contacts M₉₉ of switch M' by a wire M₁₃₀.

A power cut off relay R₆ is interposed between rectifier M₆ and relay R₂ and receives energy through a wire M₁₃₁ leading from wire M₁₁₄ and relay R₆ is connected by a wire M₁₃₁ and a line M₁₃₄ through armature switch r₄ with switches M₁₂₁ and M₁₂₄. Relay R₆ actuates an armature switch r₇ which controls a line including a wire M₁₃₂ leading from a terminal M₁₃₅ and a line M₁₃₃ leading to switch M₉. Terminal M₁₃₆ of unit M₁₀₉ connects with wire M₁₃₇ leading from power line M₁ and wire M₇ connects at M₁₃₇ with rectifier M₆.

A wire M₁₃₈ connects armature switch r₅ with terminal M₁₃₉ of unit M₁₀₉. A wire M₁₄₀ connects terminal M₁₄₁ of unit M₁₀₉ with wire M₁₁₉ to the rectifier. A wire M₁₄₂ connects terminal M₁₄₃ of unit M₁₀₉ with switches r₄, M₁₂₄ and wire M₁₂₂ which leads to switch m₁₂. A wire M₁₄₄ connects terminal M₁₄₅ with relay R₆ which is also connected by wire M₁₃₁ with wire M₁₄₄. Wire M₁₁₄ has a branch M₁₄₇ leading to terminal M₁₄₆ of unit M₁₀₉.

Unit M₁₀₉ controls the operation of relays R₁, R₂ and R₆ in such a manner as to prevent the skipping of a step of a cycle and also the premature institution of a step before the completion of a preceding step. Relay M₁₁₅ of switch M effects the institution of successive steps of each cycle and the relay M₁₁₆ of switch M retracts switch M to "home" or starting position at the end of each cycle and also at the end of a predetermined number of cycles as determined by the selector switch M'.

It may be here repeated that a normal cycle includes but four steps and the number of cycles varies in accordance with the manual setting of selector M₁₀₃ to produce studs S of a desired number of spacers and intermediate bays, and upon application of a final spacer, the cycle during which the final spacer was applied would include six steps. The two added steps of such final cycle would, in turn, operate and retract the shearing unit E. Relay M₁₂₇ of selector switch M' serves to step said switch progressively at the end of each cycle and said switch is restored to "home" or starting position by relay R₂.

Switch M can be manually stepped, but the switch M' can not be manually operated, however switch M' through selector M₁₀₃ is arranged to be manually set prior to the beginning of a series of operations to correspond to the number of bays in proposed studs and the corresponding number of spacer applying cycles.

At any point in a cycle switch M may be manually operated provided switch M' is first opened in order to remedy "skips" or to otherwise synchronize operation of the units as when a unit lags or fails, or due to the absence of a spacer in transit to or at welding position.

For example, in the event the spacer feed

cutting or transfer units are out of time, or for any reason spacers are not being moved in regular succession to the welding unit, switch M_{10} is opened, switch M_{60} is adjusted to "spacer only" position, and switch M_{10} is then turned to automatic position. Then when a spacer has arrived at a desired position, switch M_{10} is opened, switch M_{60} is adjusted to "stud" position, and switch M_{10} is again adjusted to automatic position and continuous synchronous operation is resumed.

In operation, when the main switch is closed for supplying electric current from a source to the elements of the several units, as shown in the circuit diagram, and air and fluid pressure have been established in the hydraulic and compressed systems as disclosed the machine is set for continuous operation. Reels of wire are arranged for supplying wires W , W and W' through the straightening units and thence through the feeding units B and H are advanced intermittently, step-by-step at regularly timed intervals for uniform distances after having been initially advanced manually to pre-established points of beginning. Parallel sections of wires W , W and uniform cut sections of wire W' have a common point of stoppage at the welding unit D . Following a welding operation, the then joined members are advanced through shearing position in successive steps until a predetermined number of spacers have been affixed to the longitudinal members. Under control of selector switch M' , the unit E becomes operative for cutting the longitudinal members from wires W , W in the then fifth step of a final cycle of operation and the ensuing sixth step retracts all then unretracted units, if any, to original "home" or starting positions preparatory to the beginning of the first step of the first cycle of another stud forming series. All of the control switches are mounted on a panel for ready access so that a switch may be actuated for effecting both independent manual and automatic operation of the units collectively.

The electrical hookup is such that either an operative or a retractive movement of some units will energize the solenoid and open the fluid valve of a succeeding unit and thereby effect the application of fluid pressure (either liquid or air) to and for operating the units progressively.

The essence of the invention is in the provision of a plurality of units in procession for performing different operations upon and for moving certain strands of wire longitudinally and at least another strand of wire transversely cutting the transversely moved wire into uniform sections, moving the sections intermittently to a common junction with the welder and welding the same to the longitudinal wires, and finally cutting the thus prefabricated members into sections of uniform length for use.

I claim:

1. In a machine arranged to intermittently move a pair of wires in a longitudinal path and a third wire in a relatively right angular path from separate sources to a common welding position: a shearing unit, transfer means for feeding uniform sections of said third wire from said shearing unit to a predetermined transfer position, a welding unit disposed in the paths of said pair of wires and of said sections, and a unit for delivering the sections of said third wire in single file and in succession from said transfer position and for depositing said sections in position in the welding unit between the longitudinal wires and connections between said units and a

source of power for effecting their operation in sequence, to provide a fabricated building member, said machine including means for applying fluid pressure to the sections of said third wire to effect their intermittent delivery to the receiving means therefor, said delivery unit being fluid operated and including a pair of elements for arresting the progress of a section toward the welding unit at successive stages and simultaneously operable for releasing one section for deposit in the welding unit while arresting the progress of a following section toward welding position, and vice versa.

2. In a machine arranged to intermittently move a pair of wires in a longitudinal path and a third wire in a relatively right angular path from separate sources to a common welding position: a shearing unit, transfer means for feeding uniform sections of said third wire from said shearing unit to a predetermined transfer position, a welding unit disposed in the paths of said pair of wires and of said sections, and a unit for delivering the sections of said third wire in single file and in succession from said transfer position for depositing said sections in transverse positions in the welding unit between the longitudinal wires, to provide a fabricated building member and connections between said units and a source of power for effecting their operation in sequence, said transfer means including a laterally shiftable carrier, said delivery unit including a tube offset from the plane of said third wire and positioned ahead of said shearing unit, and fluid operated means for shifting said carrier between shearing and transfer positions and for impelling the cut sections from sheared position to position for delivery to welding position, in succession.

3. In a machine arranged to intermittently move a pair of wires in a longitudinal path and a third wire in a relatively right angular path from separate sources to a common welding position: a shearing unit, transfer means for feeding uniform sections of said third wire from said shearing unit to a predetermined transfer position, a welding unit disposed in the paths of said pair of wires and of said sections, and a unit for delivering the sections of said third wire in single file and in succession from said transfer position and for depositing said sections in position in the welding unit between the longitudinal wires, to provide a fabricated building member and connections between said units and a source of power for effecting their operation in sequence, said transfer means including a laterally shiftable carrier, said delivery unit including a tube offset from the plane of said wire and positioned ahead of said shearing unit, and fluid operated means for shifting said carrier between shearing and transfer positions and for impelling the cut sections from sheared position to position for delivery to welding position, in succession, said carrier including a holder for the cut sections and disposed in a plane offset from the welding unit, and a delivery unit arranged to receive and discharge said sections to the welding unit and to deposit said sections crosswise of and in the common plane of said pair of wires whereby upon actuation of the welding unit said sections will be butt welded to said pair of wires at uniformly spaced points.

OTTO HOWARD LUCY.
